UNITED STATES PATENT OFFICE.

FREDERICK E. RAMSDEN, OF FORT DODGE, IOWA.

SCHOOL-DESK.

960,703.

Specification of Letters Patent. Patented June 7, 1910.

Application filed September 12, 1908. Serial No. 453,065.

To all whom it may concern:

Be it known that I, FREDERICK E. RAMSDEN, a citizen of the United States of America, and resident of Fort Dodge, Webster 5 county, Iowa, have invented a new and useful School-Desk, of which the following is a specification.

The object of this invention is to provide an improved construction for school desks.

10 A further object of this invention is to provide an improved construction for a combined school desk and seat.

A further object of this invention is to provide an improved construction for a 15 school desk, seat and book box.

A further object of this invention is to provide a school desk, seat and book box supported over and by a single pedestal.

20 A further object of this invention is to provide, in a school desk and seat combined, a single pedestal and seat mounted for oscillation on a vertical axis on said pedestal and also arranged for up and down adjustment, and also arranged for adjustment relative to 25 the desk.

A further object of this invention is to provide, in a school desk, a seat back susceptible of up and down adjustment and also susceptible of adjustment horizontally 30 or circumferentially on an upright axis.

A further object of this invention is to provide in a school desk, a single pedestal and a desk carried thereon, said desk susceptible to up and down adjustment relative 35 to said pedestal, and also susceptible of adjustment of inclination relative to the floor or surface on which the pedestal is carried.

A further object of this invention is to 40 provide a book box independent of yet associated with the desk and seat of the school desk, and wholly independent of any adjustment of the desk or seat.

A further object of this invention is to 45 provide an individual school desk adapted for a single occupant and susceptible of ingress or egress at one side only, and without disarranging or interfering with such desk or any adjacent desk or seat.

A further object of this invention is to 50 provide a seat or chair susceptible of horizontal oscillation to facilitate occupying or leaving said seat.

55 My invention consists in the construction, arrangement and combination of elements hereafter set forth, pointed out in my claims

and illustrated by the accompanying drawing in which—

Figure 1 is a side elevation of the complete desk. Fig. 2 is a rear elevation of the complete desk. Fig. 3 is a front elevation 60 of the complete desk. Fig. 4 is a plan of the complete desk. Fig. 5 is a detailed vertical section illustrating the construction and connection of members employed to support the seat. Fig. 6 is a horizontal section 65 on the indicated line 6—6 of Fig. 1. Fig. 7 is a detailed vertical section illustrating the construction and connection of parts employed to support the desk or shelf. Fig. 8 is a detailed cross section on the indicated 70 line 8—8 of Fig. 4 illustrating the construction of a pen and pencil holder.

In the construction of the device as shown the numeral 10 designates a base preferably formed of metal by molding. The base 10 75 may be of any desired form or contour and approximates or slopes at its margins closely to the surface of the floor on which it is carried to facilitate sweeping such floor or otherwise traversing the same. The base 10 is 80 formed with a plurality of screw holes 11 adapted to admit screws for fastening said base to the floor. The base 10 is formed with a shelf or lug 12 which in turn is provided with bolt holes 13. A pedestal or 85 standard 15, preferably formed of metal by molding, is mounted vertically on a shelf or lug 12 and is formed with a flange 16 at its lower end and provided with bolt holes 90 registering with the holes 13. Bolts 17 are mounted through the registering holes in the shelf 12 and flange 16, and are secured by nuts 18, thus rigidly connecting the pedestal to the base. A plate 19, preferably of 95 filigreed or skeleton form, is formed on or fixed to the pedestal 15 and projects forwardly and rearwardly therefrom. A similar plate 20 is provided and is arranged parallel with and outside of the plate 19. Blocks 21 are arranged between end and 100 bottom margins of the plates 19, 20, and bolts 22 extend through and rigidly connect said plates and blocks thus forming a book box open at its top and ventilated on each side. Flanges 23, 24 are formed on one face 105 of the pedestal 15 and project slightly over the base 10. Flanges 23, 24 are inclined upwardly and rearwardly and a slot 25 is formed in the pedestal between said flanges. An arm 26, preferably formed of metal by 110

molding, is mounted with one end portion fitted between flanges 23, 24 and is secured by a bolt 27 extending through said end portion and through the slot 25, and secured 5 by a nut 28 on its outer end engaging the outer face of the pedestal. The inner end portion of the arm 26 is formed with a cup 29 opening upwardly and adapted to receiving and retaining lubricating oil. A journal 30 is formed on the arm 26 centrally of the cup 29 and extends upwardly beyond the margins of said cup. A yoke 31 is provided and is formed with a hub 32 on its central portion. The journal 30 is frustum shaped 10 and the bore of the hub 32 is fitted thereto. A notch 33 is formed in the lower end portion of the hub 32 and is adapted to receive a lug 34 formed on the bottom of the cup 29. The lug 34 is of materially less length 15 than the notch 33, thus providing for a limited degree of rotation of the hub 32 on the journal 30 within the cup 29. A bolt 35 is mounted in the central portion of the journal 30 and one or more washers 36 are 20 mounted loosely on said bolt and rest on the upper end of said journal within the bore of the hub. One or more washers 37 of larger diameter are mounted on the bolt 35 and rest on the upper face of the hub 32. 25 A nut 38 is screwed on the bolt 35 and binds the washers 37, 36 and the hub 32 to the journal 30. A seat bar 39, preferably made of spring steel is mounted in notches in the extremity of the arms of the yoke 31 and is 30 secured thereto by a clamp member 40 overlying the seat bar and bolted to the yoke. The clamp member 40 is provided with an inclined hole in its rear portion and the seat bar 39 is bent upwardly and rearwardly 35 and extends through said hole. This is a provision made for preventing oscillation of the seat bar 39 on a horizontal axis. 40 A seat back 41 is provided and is carried on a bracket 42 formed with a socket 43 45 adapted to receive and be adjusted vertically on the seat bar. A set screw 44 is mounted in the socket 43 and adjustably connects said socket to the seat bar. The bracket 42 may be adjusted lengthwise of or pivotally on the 50 seat bar 39. The seat bar 39 extends forwardly from the clamp member 40 and then is curved upwardly and extends rearwardly parallel with the body portion thereof in the 55 form of an arm 45. A seat or chair 46 is mounted on and secured to the arm 45 of the seat bar by means of clamp members 47, 48 bolted together. The clamp 47 is fixed to the seat or chair 46 and is provided with a 60 concave rest for the arm 45, while the clamp member 48 is opposite to the clamp member 47 and is provided with curved seat partially embracing said arm. The seat or chair 46 may be adjusted longitudinally or circumferentially of the arm 45. The yoke 31 and 65 its hub 32, the seat bar 39, clamp member 40, arm 45, clamp members 47, 48, and seat 46 may turn on the axis of said hub to the degree permitted by the travel of the notch 23 over the lug 34 to facilitate entering and leaving the seat. The resilience of the bar 39, especially at the forward curve thereof, provides a cushion for the seat or chair 46. A bracket 49 is formed preferably of metal by molding and is provided with a slot 50 lengthwise thereof. A bolt 51 is mounted 70 through the slot 50 of the bracket 49 and is seated in the pedestal 15. By means of the slot 50 and bolt 51 the bracket 49 may be adjusted altitudinally. The pedestal 15 is provided with flanges 52, 53 vertically parallel with each other and crossing the plate 19, and the bracket 49 is formed with a groove or grooves between its side margins and fitting to said flanges. Thus provision is made to prevent oscillation of the bracket 49 on 75 the bolt 51. The bracket 49 is formed with a circular head 54 on its upper end and a circular recess or chamber 55 is formed in the outer face of said head. A bracket or spider 56, preferably is formed of metal by molding and is provided with a circular head 57 meeting the head 54 of the bracket 49. The recess or chamber 55 is frustum shaped and a conical washer 58 is mounted therein and fitted thereto. A bolt 59 is mounted through 80 the washer 58 centrally of the recess 55 and extends through registering apertures in the heads 54 and 57, and a nut 60 is mounted on the inner end of said bolt and clamps said members together. A hand wheel 61 is fixed to the outer end portion of the bolt 59 and is employed to rotate said bolt to tighten or loosen the clamp of the conical washer 58 in the recess 55, and to tighten or loosen the clamping relations between the heads 54 and 85 57. The plate or spider 56 is formed with notches in its lower face and adjacent the conical washer 58 and a lug 62 is formed on the periphery of said washer and is adapted to engage in one or another of said washers. 90 A desk shelf or table 63, preferably made of wood, is mounted on the spider or plate 56 and secured thereto by screws 64. One margin of the table or shelf 63 is adjacent to the conical washer 58 while the major portion 95 of said desk or shelf extends laterally and forwardly across and beyond the forward margin of the seat 46. In other words, reference to Fig. 4 will disclose that the seat back 41, seat 46 and desk 63 are in alignment and are in a row at one side of the book box or receptacle. No provision is made for oscillating or adjusting the desk or shelf 63 on a vertical axis but said shelf can be adjusted on the axis of the bolt 59 by loosening 100 the bolt in the nut 60 and moving said desk to the desired inclination or level position and then tightening said bolt. The interengagement of the lug 62 in the notch of the spider 56 establishes a stable relation be- 105 110 115 120 125 130

tween said spider and desk, and the washer 58 and the conical fitting of said washer in the recess 55 provides an effective clamping means or lock to hold the desk in either position in which it may be placed manually. Furthermore, the desk may be adjusted vertically as described, through the medium of the bolt 51 and slot 50.

A half round depression or groove 65 is 10 formed in the upper surface of the desk or shelf 63, adjacent the forward margin thereof and a cleat or strip 66 is mounted on said marginal portion. The cleat or strip is 15 formed with a quarter round groove 67 in one corner and is fixed to said marginal portion of the desk, in such position that the quarter round depression or groove 67 overlies and matches with the half round groove or depression 65, and conjunctively therewith provides a pen and pencil holder in the 20 upper surface of the desk. The strip 66 serves the useful purpose of preventing forward movement of pen or pencil from the groove 65 and also tends to conceal such articles from the view of persons in front of the desk.

In the practical use of the desk above described the parts are assembled as shown in Figs. 1, 2, 3, and 4, and adjusted as to the 30 height of the seat from the floor, the height of the seat back from the seat, the inclination of the seat and seat back, the height of the desk from the floor, and the inclination of the desk, to fit the pupil who is to occupy 35 and use such desk. Thereafter the pupil turns the seat in the direction of the arrow in Fig. 4 to the extent permitted by the lug 34 in the notch 33, descends upon the seat 46 and then turns in the direction opposite to that indicated by said arrow into any 40 proper position facing the shelf or desk 63.

The seat is always entered and departed from at the same side, the book box is always on the opposite side of the seat, and the 45 student may shift the position of the seat rotatively relative to the desk 63 into whatever angle is indicated, desired or most convenient. It is to be understood that the parts may be constructed and arranged in 50 reverse relations to permit of entering and leaving the seat in an opposite direction from that illustrated.

It will be understood that the construction illustrated may be modified and changed in 55 numerous particulars, and that parts thereof may be entirely eliminated without departing from the scope of my invention.

I claim as my invention—

1. A school desk comprising a single pedestal, a slideway formed thereon, an arm engaging and extending horizontally from said slideway, a bolt connecting said arm and

slideway adjustably, a seat bar carried by the outer end of said arm, a seat on one end of said bar and a back on the opposite end 65 of said bar.

2. A school desk, comprising a single pedestal formed with a slideway, an arm adjustably mounted on said slideway, and secured to said pedestal, said arm formed with 70 a journal bearing, a yoke journaled on said bearing, a seat bar on said yoke, a clamp over said seat bar and secured to the yoke, a seat on one end of said bar, and a back on the opposite end of said bar. 75

3. In a school desk, a supporting arm formed with a journal and a cup surrounding said journal, a yoke formed with a hub pivoted on said journal and extending within said cup, means for clamping said yoke 80 and journal together, a seat bar carried by said yoke, a seat on one end of said bar and a back on the opposite end of said bar.

4. In a school desk, a supporting arm formed with a conical journal and a cup 85 surrounding said journal, a yoke formed with a conical bore fitted to said journal, clamping devices connecting said journal and yoke, a resilient seat bar carried by said yoke, a clamping member mounted on said 90 yoke and engaging said seat bar, a seat mounted on one end of said bar and a back mounted on opposite end of said bar.

5. In a school desk, a supporting arm formed with a journal and a cup surrounding 95 said journal, a yoke formed with a hub pivoted on said journal, said hub formed with a notch and a lug on the cup entering said notch, a seat bar mounted on said yoke, a seat on one end of said bar and a back on 100 the opposite end of said bar.

6. In a school desk, a single pedestal, a supporting arm wholly carried by and extending laterally from said pedestal, a seat bar pivotally mounted on and extending 105 transversely of said arm, a seat mounted on and adjustable longitudinally of and pivotally on one end of said bar and a back mounted on said bar.

7. In a school desk, a single pedestal, a 110 supporting arm wholly carried by and extending laterally from said pedestal, a seat bar pivotally carried by and extending transversely of said arm, a seat on one end of said bar, and a back mounted on and adjustable 115 longitudinally of and pivotally on the opposite end of said bar.

Signed by me at Fort Dodge, Iowa, this sixth day of May, 1908.

FREDERICK E. RAMSDEN.

Witnesses.

Mrs. E. A. RAMSDEN,
CHAS. D. CASE.
